UNITED STATES PATENT OFFICE.

JAMES PHIPPS, OF PHILADELPHIA, PENNSYLVANIA, ASSIGNOR TO MARTIN LANDENBERGER & CO., OF SAME PLACE.

DESIGN FOR A NUBIA.

Specification forming part of Design No. **6,696**, dated June 3, 1873; application filed May 8, 1873.

To all whom it may concern:

Be it known that I, JAMES PHIPPS, of Philadelphia, Pennsylvania, have invented a Design for a Nubia, of which the following is a specification:

The nature of my design is fully represented by the accompanying photograph.

The body of the nubia consists of plain open knitted work A, ornamented by a border, B, and stripes C and D, composed of coarse threads interlocked with the finer threads of the body of the nubia, in a manner which will be readily understood without explanation. The border B is composed of two or more rows of scalloped threads, *a a*, combined with threads

b, waved and looped, in the manner clearly shown in the drawing. The stripes C and D are composed of rows of waved and looped threads, similar to the threads *b* of the border.

Irrespective of the colors employed, I claim—

1. The design for a nubia, having the within-described border B.
2. The whole design for the nubia, including the border B, stripes C and D, and body A.

In testimony whereof I have signed my name to this specification in the presence of two subscribing witnesses.

Witnesses: JAMES PHIPPS.

ROBERT McCONNELL,
H. DORNEMANN.
